UNITED STATES PATENT OFFICE.

LESLIE E. SPRING, OF WHITE COTTAGE, OHIO.

ENVELOP AND FASTENER.

1,112,486.

Specification of Letters Patent.

Patented Oct. 6, 1914.

Application filed November 29, 1913. Serial No. 803,777.

To all whom it may concern:

Be it known that I, LESLIE E. SPRING, a citizen of the United States, residing at White Cottage, in the county of Muskingum and State of Ohio, have invented certain new and useful Improvements in Envelops and Fasteners, of which the following is a specification, reference being had to the accompanying drawings.

10 This invention comprehends certain new and useful improvements in envelopes and has for its primary object to construct an envelop in such manner that it will be impossible for unauthorized parties to open 15 the same without being detected.

Another object is to provide an envelop of this character which will be of improved and novel form and which will be provided with locking means of such character that 20 it will be impossible to replace said locking means or any part of the same after breaking said locking means to gain access to the contents of the envelop.

A further object is to generally improve 25 and simplify the construction and operation of the devices of this character and increase the efficiency of the same without increasing the cost thereof.

With the above and other objects in view, 30 my invention consists in certain novel constructions, combinations, and arrangements of parts to be hereinafter more fully described, claimed, and illustrated in the accompanying drawings, in which,

35 Figure 1 is a plan view of the complete envelop in open position; Fig. 2 is a similar view with the envelop closed, showing the back of said envelop; Fig. 3 is a fragmentary plan view, showing a portion of the 40 back of the envelop before the insertion of the second locking means; Fig. 4 is a fragmentary view, showing a portion of the front of the envelop; Fig. 5 is a fragmentary plan view partly in section, showing the 45 manner in which the flaps are interlocked; Fig. 6 is a fragmentary plan view of one end of the front of the envelop with the flap carried thereby in extended position and the first locking member secured to the 50 same; Fig. 7 is a view similar to Fig. 6, before the application of the first locking member; Fig. 8 is an enlarged plan view of the first locking member; Fig. 9 is an enlarged sectional view through the envelop 55 after the same has been closed and locked by my improved locking means; Fig. 10

is an enlarged plan view of the second locking member; and Fig. 11 is a view similar to Fig. 9 and at right angles to the same.

Referring more specifically to the drawings in which similar reference characters designate corresponding parts throughout the several views, 1 designates the envelop which may be formed of any suitable material and has the flaps 2 and 3 turned 60 in at one end and interlocked, one of said flaps being of substantially triangular form while one corner of the remaining flap is bent around the first flap, as shown at 4.

The envelop is closed along its opposite 70 end and one longitudinal edge by rows of stitching or other suitable means, it being understood that the envelop is formed of a suitable blank bent upon itself centrally to form the opposite halves or front 5 and back 75 6 of the envelop.

A disk 7 is secured to each side of the triangular flap, adjacent the point thereof while another disk 7 is secured to the inner face of the back 6 and each disk is provided with a suitable central opening 8, it being understood that the disks 7 are placed in such manner that the openings thereof register and the portions of the envelop to which 80 said disks are secured are also provided with 85 openings registering with the openings of the disks.

A locking member 9 is carried by the disk 7 secured to the front face of the triangular flap 2, said locking member 9 having a central offset portion within which is positioned a spring clamp 10 formed by extending the legs of the U-shaped wire member 11 transversely through the offset central portion of the locking member 9.

The envelop is secured in closed position after the contents have been properly placed in said envelop, by forcing the shank 12 of the locking member 13 inwardly through the central openings of the disks 7 and parts of 100 the envelop to which said disks are secured, said shank having the semi-spherical head 14 formed upon its inner end and adapted to be forced between the legs of the U-shaped wire member 11 and thereby securely 105 clamped in the locking member 9, it being understood that the outer end of the shank is flattened, for engagement against the outer face of the back 6 of the envelop.

From the foregoing, it will be clearly apparent that after the envelop has been fastened in this manner, it cannot be opened by

- unauthorized parties without leaving traces of the act. It will be evident that should a party tampering with the envelop, break the shank 12, it will be impossible for the party 5 to disengage the head 14 from the spring clamp 10, within the offset central portion of the locking member 9 and withdraw the shank 12 to replace the same with the locking member 13 from another envelop. 10 Therefore, it will be impossible for the guilty party to destroy the evidence of their unlawful act.
- While I have shown the preferred embodiment of my invention, it will be understood 15 that minor changes in the details of construction and arrangement of parts may be made within the scope of the appended claims without departing from the spirit of my invention or sacrificing any of the advantages of the same.

What I claim is:—

A device of the class described comprising the combination with an envelop having inturned flap members, a locking plate having a central off-set portion connected to the 25 inner face of the front wall of the envelop, a U-shaped spring wire clamping member extending transversely through the off-set portion of said locking plate, a second locking plate having a shank extending through 30 the rear wall of the envelop and the inturned flap members thereof, said shank having an enlarged head at its free end for engagement between the legs of said U-shaped clamp.

In testimony whereof I hereunto affix my 35 signature in the presence of two witnesses.

LESLIE E. SPRING.
